[57] CLAIM

The ornamental design for a mailbox post, as shown and
described.

DESCRIPTION

FIG. 1 is a front elevational view of a mailbox post
showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view of a second embodiment
of a mailbox post showing my new design;

FIG. 7 is a left side elevational view thereof;

FIG. 8 is a right side elevational view thereof;

FIG. 9 is a top plan view thereof;

FIG. 10 is a front elevational view of a third embodiment
of a mailbox post showing my new design;

FIG. 11 is a left side elevational view thereof;

FIG. 12 is a right side elevational view thereof; and

FIG. 13 is a top plan view thereof.
